UNITED STATES PATENT OFFICE.

HENRY GIBBS, OF CHICAGO, ILLINOIS, ASSIGNOR TO W. D. ALLEN MANUFACTURING COMPANY, OF CHICAGO, ILLINOIS, A CORPORATION.

VALVE MECHANISM.

1,193,009.

Specification of Letters Patent.

Patented Aug. 1, 1916.

Application filed April 25, 1913. Serial No. 763,668.

To all whom it may concern:

Be it known that I, HENRY GIBBS, a citizen of the United States, and a resident of Chicago, county of Cook, and State of Illinois, have invented certain new and useful Improvements in Valve Mechanism, of which I do declare the following to be a full, clear, and exact description.

The present invention has for its object 10 to provide an improved construction of valve, more particularly designed for radiators of hot water systems, and the invention consists in the features of novelty hereinafter described, illustrated in the accompanying drawing and particularly pointed out in the claims at the end of this specification.

Figure 1 is a view in central vertical section (parts being shown in elevation) 20 through a valve mechanism embodying my invention. Fig. 2 is a view in horizontal section on the line 2—2 of Fig. 1. Fig. 3 is a view in vertical section (parts being shown in elevation) on line 3—3 of Fig. 1. 25 Fig. 4 is a detail perspective view of the cylindrical valve. Fig. 5 is a detail perspective view of a shifter for connecting the valve to its stem.

The casing 10 of the valve is formed with 30 the usual channels 11 and 12 for the passage therethrough of water. The interior of the casing 10 is made truly cylindric to receive the valve 14 and when the parts are in readiness for use, this valve 14 will occupy 35 the position shown in Fig. 1 of the drawing. This valve 14 is a cup-shaped valve formed from sheet metal, the body of the valve being truly cylindric, while the top of the valve is preferably slightly crowned. 40 Through the body of the valve 14 is formed an opening 15 adapted to register with the passage 12 in the valve casing. In the top of the valve 14 are formed the holes 16 and 17, the central hole 17 serving to receive 45 a squared portion 18 of the valve stem that passes through the upper portion of the casing. The lower end of the valve stem is screw-threaded, as at 20, to receive the retaining nut 21, and preferably a washer 22 50 is interposed between the nut 21 and the under side of the top of the valve 14. The squared portion 18 of the valve stem also passes through a correspondingly squared opening 25 in the stop plate 26. This stop

plate 26 is provided with the lugs 27 adapted 55 to pass through the openings 16 in the top of the valve 14, so that when the stop plate 26 is rotated by the turning of the valve stem, a corresponding rotation will be imparted to the valve 14. The stop plate 26 60 occupies a position within the casing immediately above the top of the valve 14 and this stop plate is provided with a stop arm 29 that is adapted to contact with the shoulders 30 formed in the valve casing, so as to 65 limit the extent of rotation of the valve 14. When the stop arm 29 of the stop plate is against one of the shoulders 30, the valve will be in completely open position, as illustrated in Fig. 1, and when the stop arm 29 70 is brought into contact with the opposite shoulder 30, the valve 14 will be in completely closed position.

Above the opening 32 in the top of the valve casing, through which opening the 75 valve stem passes, is formed an annular shoulder 33 forming a valve seat against which bears a supplemental valve 34 carried by the valve stem. Preferably this supplemental valve consists of a fiber washer 80 35 against which bears an annular flange or shoulder 36 that is integral with or rigidly secured to the valve stem. This supplemental valve sets within a stuffing box 37 that is formed in the upper part of the casing, and in this stuffing box and around the valve stem suitable packing 38 will be placed, this packing being held in position by an annular gland 39 through which the valve stem passes. A collar 40 sets over the 85 gland 39 and the lower portion of this collar is screw-threaded to engage the correspondingly exteriorly threaded wall of the stuffing box 37. That part of the valve stem that passes through the stuffing box gland 39 and 90 the collar 40 is cylindrical and to the upper end of the valve stem is removably connected a hand wheel 45 by which the valve stem will be turned.

From the foregoing description it will be 100 seen that when the valve 14 is in the position illustrated in Fig. 1 of the drawings, water may pass freely through the valve casing. When, however, it is desired to cut off the flow of water, the valve will be turned by 105 manipulating the hand wheel 45, until the valve more or less closes the port 12 of the casing.

It will be observed that the opening 15 in the valve 14 is some distance above the bottom of the valve, so that sufficient metal is left to give rigidity to the valve and guard 5 against danger of its being distorted. Inasmuch as the valve is stamped from sheet metal, it can be formed truly cylindric and the necessity of machining the surface of the valve is avoided.

10 My present construction of valve mechanism is much more effective than that familiar type of radiator valve mechanism in which the valve and valve stem are formed integral. One serious objection to forming 15 the valve and valve stem integral is that it is extremely difficult to machine the outer surface of the valve, so that it shall be both truly cylindric and in exact alinement with the valve stem. Another marked ad- 20 vantage of my present invention is the em- ployment of the supplemental valve on the valve stem and arranged to coöperate with an annular seat or shoulder at the inner end of the stuffing box. By this arrangement, 25 the stuffing box can be repacked without danger of leakage, it being simply necessary during such repacking operation to tightly force the supplemental valve against the annular shoulder or valve seat 33. A fur- 30 ther advantage of my present construction is that the supplemental valve 34 arranged, as it is above the shoulder 32 of the valve casing, will prevent any forcible depression of the valve that might tend to disarrange 35 its location within the casing. Valves of this character are frequently located adja- 40 cent the floor, and it will therefore be perceived that it is a decided advantage to guard against any danger of the disarrange- 45 ment of the valve within the casing incident to accidental pressure of the foot upon the hand-wheel at the outer end of the valve stem.

The precise details of construction can be varied without departure from the spirit of 45 the invention and features of the invention may be employed without its adoption as an entirety.

Having thus described my invention, what 50 I claim as new and desire to secure by Letters Patent is—

1. Valve mechanism of the character de- 55 scribed, comprising a casing formed with channels arranged at an angle to each other for the passage of fluid through the casing, the interior of the casing having a truly cylindric chamber, an inverted cup-shaped valve formed from a single piece of thin sheet metal having a truly cylindrical body 60 to engage and snugly fit within said casing, one side of said valve being formed with an opening to register with a channel of the casing and the top of said valve being formed with a hole, a valve stem passing through the hole in the top of the valve, a

plate arranged at the top of said valve and within the upper part of the valve casing and being interlocked with said valve stem and said valve, means for preventing the downward pressure of said valve stem upon the top of said valve, and means for limiting the rotation of said valve stem. 70

2. Valve mechanism of the character de- 75 scribed comprising a casing formed with channels for the passage of liquid, said cas- ing having a cylindrical chamber with which said passages connect, an inverted, cylindri- 80 cal, cup-shaped valve formed of thin sheet metal located within and fitting snugly against the wall of said cylindrical chamber, said valve having an opening in its side to register with one of said passage ways and having a perforated top, said casing having a wide bottom opening to admit the valve and the top of said casing having a con- 85 tracted opening above the top of said valve, a valve stem passing through said contracted opening of the casing and engaging the per- 90forated top of said valve, and means for preventing the downward pressure of said 95 valve stem upon the top of said valve comprising an annular part secured to said valve stem of greater diameter than and located above the contracted opening of the casing through which the valve stem passes. 100

3. Valve mechanism of the character de- 105 scribed comprising a chambered casing pro- vided with channels for the passage of fluid, an inverted cup-shaped valve arranged with- 110 in said casing, said valve being open at its bottom and being provided with an opening in one side, the top of said valve being pro- vided with a plurality of holes, a valve stem passing through one of the holes in the top of said valve, means within the valve for 115 engaging the lower end of said valve stem to secure it to the valve, and a stop plate ar- ranged between the top of said valve and the top of the chamber of said casing, said stop plate having a projection passing through one of the holes in said valve and having a laterally projecting arm, the interior of the upper part of said casing being provided with shoulders to be engaged by the arm of 120 said stop plate. 125

4. Valve mechanism of the character de- 125 scribed comprising a casing having channels for the passage of liquid therethrough and having a cylindrical chamber within the top of which are provided shoulders, an in- 130 verted cup-shaped valve within the chamber of the casing, said valve having an open bot- tom and having an opening in one side, the top of said valve being formed with a central polygonal opening and with openings at the side thereof, a stop plate interposed between the top of said valve and the top of the chamber of the valve casing, said stop plate being provided with a polygonal opening and with downwardly extending projec- 130

tions to pass through the openings in the top of the valve and with a laterally extending arm to engage the shoulders within the top of the valve casing, and a valve stem passing through the top of the valve casing and having a polygonal portion passing through said stop plate and through the central

hole in the top of the valve, and means within the valve for securing the valve to the valve stem.
